UNITED STATES PATENT OFFICE.

DANIEL CUSHING, OF LOWELL, MASSACHUSETTS.

METALLURGICAL FURNACE.

Application filed July 19, 1926. Serial No. 123,279.

This invention relates to a furnace for metallurgical operations, particularly adapted to the reduction of non-ferrous metals such as copper, brass, bronze, zinc or tin.

5 It is the object of my invention to improve such a furnace in several important respects, by which improvements the furnace is better adapted to its intended purposes and by which more satisfactory results are attained.

10 In the operation of such a furnace with non-ferrous metals in the form of chips or light scrap, I preferably use a pitch coke or a coke of high compressive strength and substantially free from impurities.

15 A more specific object of my invention is to provide a furnace for such purposes in which the bottom of the cupola or body portion is closed by a bottom member or removable plate which is provided with a refractory lining, commonly fire brick, and which bottom member may be moved to open position for dumping and cleaning the furnace without disturbing the lining material supported thereby.

20 25 A further object of the invention is to provide improved means for regulating the draft and for permitting interchangeable use of forced or natural draft or any combination thereof, but this feature is not claimed herein as it forms the subject matter of a divisional application Serial No. 325,557, filed by me December 12, 1928.

My invention further relates to arrangements and combinations of parts which will 30 be hereinafter described and more particularly pointed out in the appended claims.

A preferred form of the invention is shown in the drawings in which

Fig. 1 is a side elevation of a metallurgical furnace embodying my improvements;

Fig. 2 is a plan view thereof;

Fig. 3 is a partial sectional elevation, taken substantially along the line 3—3 in Fig. 2;

Fig. 4 is a plan view of the bottom member; and

Fig. 5 is a detail sectional view of a portion of one of the draft regulating devices.

Referring to the drawings, I have indicated a metallurgical furnace comprising a 50 cupola or body portion 10 and a stack 11 connected thereto. The cupola has the usual fire brick lining and is provided with a charging door 12, a clean-out door 13, a breast block 14 and a tap spout or runner portion 15, all of 55 substantially the usual construction. The

breast member 14 is preferably made as a single unit formed of fire brick or other similar refractory material and the opening therein is closed by clay or other material when the metal is not flowing. The cupola 10 is supported upon an annular frame member 10^a, mounted on legs 17. The cupola is provided with a plurality of spaced tuyère blocks 20, (Fig. 3) each having a tuyère opening 21 formed therein. Each block 20 preferably consists of a single piece of refractory material with a tuyère opening formed directly in said material. These blocks 20 form part of the subject matter of my divisional application above noted.

An outwardly projecting cylindrical member 23 is provided for each tuyère block 20 and forms a portion of the tuyère structure. A fan F or other source of air under pressure is connected by pipes 24, 25 and 26 to the cylindrical member 23 previously described, and the tuyère blocks are thus supplied with air under any desired pressure, depending upon the size and speed of the fan F.

The outer ends of the cylindrical projections 23 are provided with a series of spaced air openings 30 (Fig. 5) which are covered by a cylindrical cap or sleeve 31 having a series of similar air openings 32. The openings 32 are spaced apart so that the imperforate portions of the cap between the openings are of sufficient width to close the openings 30 when aligned therewith.

The end portions 33 of the caps 31 are 90 preferably provided with central openings 34 through which the interior of the furnace may be inspected and each opening 34 is preferably closed by a glass or mica disc 35. Each cap 31 may also be provided with a slot 95 36 and binding screw 37 by which said cap may be held in desired angular adjustment.

I attain very important advantages by the combination of forced and natural draft which I have shown and above described. 100 With this combination, I may close the openings 30 and operate on the forced draft entirely or I may uncover the openings 30 partially, thus modifying and reducing the forced air pressure to any desired extent. I 105 may also shut off the fan F and operate entirely under natural draft, regulating the natural draft by the angular positions of the caps 31.

This double control of the air supply has 110

been found extremely useful in carrying out metallurgical operations upon non-ferrous metals, where it is extremely essential that excessive draft be avoided.

5 Another important feature of my invention relates to the improved means which I have provided for closing the lower end of the cupola or body portion 10. For this purpose I provide a bottom member 40, pivoted 10 at 41 to bearing members or ears 42 extending downward from the annular bottom frame member 10^a of the furnace. The member 40 is provided with an upwardly extending angular flange 45 and with an outwardly 15 extending annular rim portion 46. The flange 45 is also provided with an internal rib 47, for a purpose to be described. The outwardly extending rim portion 46 engages the annular base member 10^a and forms a 20 sealing member therefor.

A cross bar 48 extends between the arms 49 on which the bottom member is pivoted, and the member 40 may be swung upward to operative position by placing a lever 50 under 25 the member 40 and over the cross bar 48. When the bottom member 40 has been moved to raised position, a post or brace 51 may be inserted to hold the member 40 in such raised or operative position. A chain 52 may be 30 provided to limit the swinging downward movement of the bottom member.

When in operation, the bottom member 40 supports a lining preferably formed of fire brick 54 fitted within the circular flange 45 35 and having grooves 55 in their edge portions adapted to fit over the rib 47. A layer of heat insulating material 56 is preferably provided between the bottom member 40 and the bricks 54. The lining is thus retained firmly in 40 operative position by the rib 47 and may be additionally secured within the flange 45 by suitable cement if desired.

The bricks are so firmly secured in position that the bottom member 40 may be swung 45 to operative or inoperative positions without disturbing the lining of the bottom member 40.

After the bottom member has been raised to the position shown in Fig. 3, the opening 50 around and above the flange member 45 may be closed by a suitable sealing material 57, such as fire clay or cement, this sealing material being easily displaced as the bottom member swings downward. The upper face 55 of the fire brick 54 and of the sealing material 57 preferably forms an inclined surface substantially at the level of the tap opening 58, so that the molten metal in the bottom of the furnace may flow freely to the tap 60 spout 15.

In actual operation, I have found that a bottom member constructed as above described, and particularly when provided with the insulating material 56, the fire brick 65 lining 54 and the sealing material 57, is ex-

tremely well adapted for use in a furnace designed for melting non-ferrous metals, especially when in the form of light chips or scrap. Such a bottom member may also be very conveniently removed for repairs or replacement. 70

Furthermore a great amount of time and labor is saved by the provision of my removable bottom member, as the furnace may be opened and cleaned at any time desired without disturbing the fire brick lining of the bottom, and it is only necessary to replace the sealing material 57 to place the furnace again in condition for operation. 75

Having thus described my invention and the advantages thereof, I do not wish to be limited to the details herein disclosed otherwise than as set forth in the claims, but what I claim is:—

1. A metallurgical furnace comprising a cupola portion, and a removable bottom member having a fire resisting lining permanently secured thereto and movable to and from operative position as a unit therewith, said bottom member and said fire resisting lining 85 having portions forming locking engagement 90 to positively retain said lining in position and the upper surface of said lining being in direct contact with the metal in the furnace and being inclined downward toward the tap 95 spout of the furnace and having its lowest edge portion adjacent and substantially on the level with said spout.

2. A metallurgical furnace comprising a cupola portion, and a removable bottom member having a fire resisting lining permanently secured thereto and movable to and from operative position as a unit therewith, said bottom member having an upwardly extending flange portion with an internal rib thereon and said lining being formed of fire brick fitting within said flange and grooved to receive said internal rib and retained in position thereby. 100

3. A metallurgical furnace comprising a cupola portion and a removable bottom member having a fire resisting lining permanently secured thereto and movable to and from operative position as a unit therewith, said bottom member having an upwardly extending flange portion and said lining being formed of fire brick secured within said flange portion, and said bottom member having a layer 110 of heat insulating material interposed between said member and said fire brick. 115

4. A metallurgical furnace comprising a cupola portion, and a removable bottom member having a fire resisting lining permanently secured thereto and movable to and from operative position as a unit therewith, said bottom member having an upwardly extending flange portion and said lining being formed of fire brick secured within said flange portion, said furnace having also a portion of sealing material disposed around and over 125 130

said flange portion when the bottom member is in operative position to seal the bottom member in said furnace.

5. In a furnace, a cupola portion having an annular base member with a substantially horizontal bottom face, and a bottom member hinged thereto comprising a substantially flat body portion positioned at an oblique angle to the horizontal when in operative 10 position, an annular flanged portion projecting from one side thereof, and an annular

sealing rim surrounding said flat portion and at an oblique angle thereto and engaging said horizontal bottom face, said annular flange projecting upwardly from said flat body portion and being adapted to be received within the lower part of the cylindrical cupola when the bottom member is in operative position.

15 In testimony whereof I have hereunto affixed my signature.

DANIEL CUSHING.
